UNITED STATES PATENT OFFICE.

FREDERICK W. PENDERGAST, OF CAMBRIDGE, MASSACHUSETTS.

MOP.

1,222,662.

Specification of Letters Patent. Patented Apr. 17, 1917.

Application filed October 24, 1916. Serial No. 127,348.

To all whom it may concern:

Be it known that I, FREDERICK W. PENDERGAST, a citizen of the United States, residing at Cambridge, in the county of Middlesex and State of Massachusetts, have invented new and useful Improvements in Mops, of which the following is a specification.

This invention relates to a mop composed of fibrous filaments attached to one end of an elongated handle, the central portions of the filaments being clamped to the end of the handle and the end portions thereof depending to form a circular mop body.

The invention has for its chief object to provide an improved construction of the handle and the means for securing the mop filaments thereto, the construction being of such nature that the component parts may be advantageously assembled by blind people to form a strong durable and satisfactory mop.

The invention is embodied in the improvements which I will now proceed to describe and claim.

Of the accompanying drawings forming a part of this specification,—

Figure 1 represents a side elevation of a mop embodying the invention.

Fig. 2 represents a section on line 2—2 of Fig. 1.

Fig. 3 represents a sectional view showing the handle and the filament-securing means as relatively arranged prior to the operation of applying and securing the mop filaments.

Fig. 4 represents a top plan view of the parts represented by Fig. 3, and in addition thereto a plurality of bunches of mop filaments extending in various directions across the end of the handle.

Fig. 5 represents a perspective view of the part hereinafter called the spider.

In the drawings,—12 represents a handle which is preferably a somewhat elongated wooden rod adapted at one end portion to be grasped by the hand of the user. The opposite end portion of the handle is of circular form and constitutes a clamping end face against which the mop filaments are clamped. I prefer to provide a recess in the clamping end of the handle, thereby forming a concave or cupped clamping face 13 surrounded by an annular ridge 14.

In making up a mop, the handle 12 is mounted vertically on a suitable support with its clamping face 13 upward, as indi-

cated by Fig. 3. A member, such as a wire nail having a single shank 15 and a head 16, is then inserted in an orifice 17 in the center or hub portion 18 of a spider, formed as 65 hereinafter described, and driven partly but not to the full extent into the handle, the nail being driven into the center of the face 13 and into the longitudinal center of the handle and extending lengthwise of the 63 handle.

The operator now places upon the end face of the handle a plurality of bunches 19 of mop filaments, preferably composed of strands of cotton yarn or thread. The 70 central portions of the bunches are laid upon the end face of the handle, the spider being held raised by the operator and laterally confined by the nail until the desired number of bunches have been inserted or assembled. As indicated by Fig. 4, the bunches 19 extend in various directions, the central portions of some of the bunches extending across those of other bunches. When enough bunches have been assembled 80 to form a flexible mop body 19^a of suitable size, the securing member 15 is driven farther into the handle, as indicated by Fig. 2, thus causing the spider to compress the central portions of the bunches and press some 85 of the filaments into the concave face 13. The operation of completing the driving of the member 15 therefore causes the brush filaments to be securely clamped in place so that they cannot be displaced endwise. 90

The spider which is formed to bridge the end face of the handle, includes arms radiating from the hub portion 18, as shown by Fig. 5, said arms having inwardly projecting fingers 20 which abut against the margin of the end face and laterally confine the bunches as indicated by Fig. 4.

The concave end face 13 having the marginal ridge 14 coöperate, with the spider and its fingers in firmly clamping the central 100 portions of the filaments.

The fingers 20 abutting against the margin of the end face are interposed between the adjacent bunches of filaments and securely confine said bunches without being 105 visible at the exterior of the mop.

The fastening member, composed of a single headed shank driven into the longitudinal center of the handle, is free from liability of splitting the handle, and is adapted 110 to be easily driven without liability of deflection or crippling.

I claim:—

A mop comprising a handle having a clamping end face, mop filaments arranged in bunches the central portions of which extend across said face in various directions, a clamping spider formed to bridge said face and composed of an apertured central hub and arms radiating therefrom and provided at their outer ends with inwardly projecting fingers, which abut against the margin of said face, and a securing member composed of a shank passing through the hub aperture, driven into the longitudinal center of the handle, and extending lengthwise thereof, and a head bearing on the outer side of the spider hub, said securing member being adapted when partially driven, to confine the spider spaced from said end face while the filaments are being assembled, and when completely driven to cause said fingers to abut against the margin of said face.

In testimony whereof I have affixed my signature.

his
FREDERICK W. X PENDERGAST.
